Primary Examiner — Catherine S Posthauer*(74) Attorney, Agent, or Firm* — Eric Karich; Karich & Associates**(57) CLAIM**

The ornamental design for a canister lid, as shown and described.

DESCRIPTION

FIG. 1 is a perspective view of a canister lid, showing my new design, shown in an environment of use with an exemplary canister;

FIG. 2 is a perspective view thereof, showing the exemplary canister removed;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines are shown for the purpose of illustrating environmental subject matter of an exemplary canister and form no part of the claimed design.

The logo in the drawings is a registered trademark of Freyian® and forms part of the claimed design.**1 Claim, 3 Drawing Sheets**(56)
